United States Patent Office

Des. 213,253
Patented Jan. 21, 1969

213,253

KEY RING

Harrington Moore, 100 Beaver St., Acton, Mass. 02154

Filed May 2, 1968, Ser. No. 11,759

Term of patent 14 years

U.S. Cl. D50—4
Int. Cl. D3—99

FIG. 1

FIG. 2

FIG. 3

FIG. 4

FIGURE 1 is an elevational view of a key ring showing my new design;

FIGURE 2 is an end view of the same, the view of each end being the same as that of the other;

FIGURE 3 is a top plan view of the same; and

FIGURE 4 is a bottom plan view of the same.

I claim:

The ornamental design for a key ring, as shown and described.
